United States Patent Office

Des. 181,611
Patented Dec. 3, 1957

181,611

BASTING BRUSH OR THE LIKE

Lawrence R. Schumann, Boston, Mass.

Application August 29, 1956, Serial No. 42,765

Term of patent 14 years

(Cl. D9—2)

Fig. 1

Fig. 2

Figs. 1 and 2 are side and rear elevational views, respectively, of a basting brush or the like, showing my new design.

I claim:

The ornamental design for a basting brush or the like, substantially as shown.
